UNITED STATES PATENT OFFICE.

SIDNEY B. SMITH, KIRKSVILLE, MISSOURI.

FENCE.

SPECIFICATION forming part of Letters Patent No. 269,892, dated January 2, 1883.

Application filed June 13, 1882. (No model.)

To all whom it may concern:

Be it known that I, SIDNEY B. SMITH, a citizen of the United States, residing at Kirksville, in the county of Adair and State of Missouri, have invented certain new and useful improvements in Fences; and I do hereby declare the following to be a full, clear, and exact description of my invention, such as will enable others skilled in the art to which it applies to make and use the same, reference being had to the accompanying drawings, and to the letters or figures of reference marked thereon, which form a part of this specification.

The object of my invention is to provide a simple, durable, and inexpensive portable panel-fence of wire or boards that may be readily removed from place to place, and yet when properly put down shall be stronger than ordinary fences.

To this end my invention consists principally in making the panels of ordinary length, with light posts the height of the panels, and in joining the panels together by a wire loop on the end of a stay thrown over the two end posts brought together, while the lower end of the stay is fastened to the ground by another wire loop on the lower end of the stay, having a shouldered peg or stake driven through it, the bottom of the end posts being also joined by a similar wire loop passing around both posts and engaging with a shouldered peg or stake driven into the ground instead of driving the posts. The middle posts may also be stayed by my plan, if desired, and wire fences may also be stayed longitudinally in a similar manner. The invention will be pointed out in the claim.

Referring to the drawings, Figure 1 is a view of the two end posts of the panels brought together, showing the loop and peg at the bottom and the loop and stay at the top, also the peg and loop fastening the stay to the ground. Fig. 2 is a perspective view of the stay, showing the loops at top and bottom.

Similar letters of reference indicate like parts in the several views.

A and B are the posts, notched and secured together at the bottom ends by loop *e* and stake *f*, as shown, post A having also a block or projection, *a*, at the top to engage with the upper end of the stay.

C is the stay, having wire loops *c c'*, secured to its respective ends in any suitable manner, the loop *c* passing over and holding the upper ends of the two posts together, and the loop *c'* passing over the short shouldered stake or peg *d*. Wire fences may also be made in portable panels, and the same secured together and to the ground in a similar manner.

From the foregoing description it is obvious that this fence may be readily removed by drawing the stakes or pegs, and may be as readily reset at any suitable place by bringing the posts together and driving the stakes.

It is also obvious that the durability of the fence is greatly increased, as the posts are not driven into the ground to decay, and make the fence worthless before the upper portion has served its time, the stays only requiring to be renewed from time to time.

Having thus described my invention, what I claim as new, and desire to secure by Letters Patent, is—

In a portable fence, the overlapping panel-posts A and B, wire loop *e*, and single-notched stake, *d*, in combination with block *a*, wire *c*, supporting stay *C*, wire loop *c'*, and notched stake *d'*, substantially as and for the purpose specified.

In testimony whereof I affix my signature in presence of two witnesses.

SIDNEY B. SMITH.
